KNITTING MACHINE

Edwin Wildt, Henry Harold Holmes, and John Cyril Herbert Hurd, Leicester, England, assignors to Wildt and Company Limited, Leicester, England, a British company

Application August 28, 1944, Serial No. 551,518
In Great Britain September 6, 1943

13 Claims. (Cl. 66—135)

This invention concerns knitting machines and has for its object the provision of a machine for producing fabric involving a combination of structure and pattern effects such as that disclosed in the specification of our co-pending application Serial No. 551,519.

In the accompanying drawings,

Figure 1 is a vertical sectional view of so much of the head of a circular knitting machine of the superposed rotary needle cylinder type as is necessary to illustrate the application of the invention thereto,

Figures 2 and 2A are developed views of the cam systems of the machine as seen from inside the top and bottom cam boxes,

Figure 3 is a detail vertical sectional view of the shogging mechanism with which the machine is furnished,

Figure 4 is a plan view of this mechanism, and

Figure 5 is a detail plan view of a portion of a dial cam system of the machine showing cams for controlling and operating the lap or wrap thread guides.

Like parts are designated by similar reference characters throughout the drawings.

Referring to Figure 1, the circular knitting machine therein shown includes rotary bottom or plain and top or rib needle cylinders 1 and 2 respectively. Double-ended latch needles such as 3 are provided for operation in these cylinders, which latter are also furnished with sliders 4 for operating the needles, when knitting, and for transferring needles from one cylinder to the other for purposes now well known to those acquainted with the art concerned. To each needle 3 there are two sliders 4, one in the bottom cylinder 1 and the other in the top cylinder 2. The customary holding down sinkers or web holders for co-operation with the needles are indicated at 5, and at 6 is shown a verge to assist in rib knitting. A cam box 7 surrounding the bottom cylinder houses cams for operating and controlling the sliders in that cylinder, while for similarly operating and controlling the sliders in the top cylinder there are cams in an associated cam box 8. For producing interlock fabric with webs of 1/1 rib combination, the bottom and top needle operating sliders 4 are set out in the manner illustrated in Figure 2. In this figure, however, only such of the sliders as are actually in operation for the production of such fabric are shown, all of the remaining, i. e. idle, sliders being omitted for the sake of clarity: in practice there would, of course, be a slider 4 in each of the tricks 1a

and 2a in the cylinders 1 and 2 respectively. Of the sliders shown there are two independently operable sets, those of one set being marked A and those of the other set being marked B. One half of each set of sliders are in alternating relationship in the bottom cylinder, and the remainder of each set in similar relationship in the top cylinder. In other words, the sliders 4A alternate with the sliders 4B in both of the needle cylinders. The plain and rib needles respectively engaged with the bottom and top sliders 4A co-operate to knit one of the ribbed webs, whilst the plain and rib needles engaged with the corresponding sliders 4B similarly co-operate to knit the other ribbed web of the fabric. In this machine there are also four circumferentially spaced feeders, viz. two odd feeders F¹ and F³ and intervening even feeders F² and F⁴, for supplying yarns y and y¹ independently to the respective sets of needles, together with different sets of cams for operating the said sets. The two webs are therefore in effect independently knitted but have crossed sinker wales as a result of which an interlocking structure is produced. To this end the sliders 4 in the respective sets are provided with butts in different planes and are appropriately prearranged in the bottom and top cylinders in conjunction with appropriate cam systems respectively disposed in the bottom and top cam boxes 7 and 8 suchwise that the two sets of needles knit respectively at the spaced feeders. Thus, as will be seen, the sliders 4A in the bottom cylinder are each formed with a knitting butt b accommodated in an upper track T¹ in the cam box 7. In this track there are, at each of the two odd feeders F¹ and F³, a clearing cam 9, a cam 10 for retracting appropriate needles to an extent sufficient to enable them to take knitting yarn y and a plain stitch cam 11. Similarly, the co-operating sliders 4A in the top cylinder are each formed with a knitting butt b¹ accommodated in a track T² in the top cam box 8. At the feeder F¹, in the track T², there is a clearing cam 12, a cam 13 for withdrawing appropriate rib needles to feeding level at which they take another yarn y and a rib stitch cam 14, whereas at the feeder F³ there is another stitch cam 14 and the feeding level is indicated at 15. The sliders 4B in the bottom cylinder are each formed with a knitting butt b² accommodated in a lower track T³ in the cam box 7 in which track—at each of the two even feeders F² and F⁴—there is a cam 16 for positioning the needles engaged with the said sliders 4B at feeding level at which they

take knitting yarn y^1 , followed by a plain stitch cam 17. At the feeder F², moreover, the cam 16 is preceded by a clearing cam 18. Again, the sliders 4B in the top cylinder are formed with knitting butts b³ which travel in a track T⁴. At each of the even feeders F² and F⁴ in the last mentioned track there is a cam 19 for positioning rib needles at the feeding level and a rib stitch cam 20. A clearing cam 21 is also provided at the feeder F². For convenience in the following further description, the four knitting stations, reading from left to right of Figure 2, are designated by the reference letters K¹, K², K³ and K⁴.

As will be understood, with the cam systems described the two sets of needles knit at the feeders alternately.

Each of the sliders 4 in the bottom cylinder is also provided with a transfer butt tb for engagement at appropriate times with a bottom transfer cam 22 whereby the slider is raised to position its needle for transference to the opposing slider in the top cylinder. Similarly, each of the sliders in the top cylinder is provided with a transfer butt tb¹ for engagement, when occasion demands, with a top transfer cam 23 adapted to advance the slider to position the needle then engaged thereby for transference to the opposing slider in the bottom cylinder. Whenever a bottom slider is raised by the transfer cam 22, the opposing slider is advanced by reason of engagement of its butt tb¹ with a cam 24 to an extent sufficient to receive the needle thus transferred from the bottom to the top cylinder. In a similar way, bottom sliders are raised by a cam 25 to receive needles transferred downwardly from the top to the bottom cylinder. It will be noted that the bottom and top transfer cams 22 and 23 are located between the knitting stations K¹ and K³. Moreover, between the knitting stations K³ and K⁴ are two further transfer cams 26 and 27 in the tracks T³ and T⁴ for engagement, when required, with the knitting butts b² and b³ respectively. Needles associated with bottom sliders raised by the transfer cam 26 are received by top sliders which latter are advanced by a cam 28 for this purpose. A cam 29 raises bottom sliders to enable them to receive needles transferred thereto by the transfer cam 27. The arrangement of the transfer cams in relation to the four knitting stations is such that immediately following transference of a needle in either set from one cylinder to the other that needle is passed through a knitting station and thereby restored to such a level that it can pass a knitting station at which needles of the other set knit.

In combination with the machine there is provided embroidery mechanism of the general character described in the specification of United States Patent No. 2,292,941. This mechanism includes a single circular series of lap or wrap thread guides such as that shown at 30 in Figure 1, said guides being arranged in a horizontally disposed dial 31 which is mounted within the needle cylinders 1 and 2 concentrically therewith. There are as many guides 30 as there are needles of one set in the bottom cylinder. The dial is provided with a flanged portion 31a to enable it to be supported by an annular support 32. This support is flanged at 32a and thereby adapted for movement circumferentially between two superposed supporting rings 33 and 34 attached both to each other and to the top cylinder 2. By reason of this construction the dial can be shogged as and for the purposes hereinafter de-

scribed. Each of the thread guides 30 is formed at its operative end with a downwardly directed right angular extension 30a which is laterally bent in the manner depicted in Figure 5. The upper edge of each thread guide is formed with a butt 30b for engagement with suitable operating cams. In addition each guide has a rearwardly extending tail butt 30c so as to enable same to be used in conjunction with selecting means for controlling the operation of the guides according to the effects to be achieved. The tail butts are provided at respectively different levels so as to be located in correspondingly different planes heightwise. As shown in Figure 1, the thread guides are initially formed with a plurality of frangible tail butts 30c which can be readily broken off according to requirements. A stationary cam plate 35 is supported above the dial 31 and on its underside is furnished with appropriate cams for action on the butts 30b. For action upon the tail butts 30c at each feeder there is provided a horizontally disposed selector cam 36 (Figures 3 and 5) which is movable vertically into any one of the aforesaid different planes in which tail butts are located, or to a neutral position clear of said butts, according to patterning requirements. Each selector cam 36 advances appropriate embroidery thread guides 30 for lapping or wrapping purposes and is arranged and operated substantially as described in the prior specification aforesaid. The embroidery threads are supplied by selected guides 30 to appropriate needles in the bottom cylinder at the same level as that at which the yarns y and y¹ are fed. That is to say, before it is lapped or wrapped by an embroidery thread, a needle is withdrawn somewhat by reason of the corresponding slider being engaged by one of the cams 10 or 16, as the case may be. Accordingly, each of the knitting stations in the bottom cam box 7 is also a wrapping station. When, with the arrangements described, a wrapping action takes place either at the feeder K¹ or K³, the needles associated with the sliders 4A are out of the range 45 of the lap or wrap thread guides 30 which latter are at this time selected to wrap only needles associated with sliders 4A. Conversely, when wrapping at feeder K² or K⁴, needles associated with the sliders 4A are out of the range of the guides 30.

If desired, the alternative thread guide selecting mechanism described in the prior specification may be used.

For shogging the dial 31 the constructional form of shogging mechanism shown in Figures 3 and 4 and fully described in the aforesaid prior specification is employed. Briefly, the shogging mechanism comprises a stepped cam 37 which is connected to a disc cam 38 and mounted upon a bracket 39 fixed upon the supporting ring 34, pattern controlled plungers or tappets 40 and 41 arranged for action upon the stepped cam 37 to impart turning movement to the latter and hence also to the disc cam 38 one or more steps in one direction or the other, and connections between said disc cam and the annular support 32 whereby the latter can be shogged one or more times in one direction or the other to a required extent. As shown in Figure 4, said connections include a pivoted lever 42 adapted to be acted upon by the disc cam 38, and a shoe 43 on this lever which engages a member 44 mounted to move bodily with the annular support 32.

Alternatively, the needles may be shogged in relation to the thread guides.

Instead of selectively operating the thread guides, the cylinder needles may be selectively operated as by pattern controlling selecting means including a rotary wheel, drum or jacquard band and racking mechanism, with or without intermediate selectors, and operated in the manner aforesaid, so that selected needles are moved lengthwise, e. g. raised or lowered, in relation to the guides suchwise that only needles which are raised or left raised are lapped or wrapped with embroidery threads.

All of the embroidery thread guides may be supplied with threads of the same character or colour, so that if a succession or all of the needles in the bottom cylinder are lapped or wrapped, horizontal striping effects of a corresponding solid character or colour will be produced. Alternatively the guides may be supplied with contrasting threads alternately, or in any other desired order, so that if a succession or all of the needles in the bottom cylinder are lapped or wrapped, horizontal striping with corresponding contrasting effects, coursewise, will appear in the knitted fabric. By suitable shogging of the thread guides contrasting solid horizontal striping effects are produced in desired sequence walewise. For example, black threads may be supplied to the guides corresponding with needles which knit at one feeder, and red threads may be supplied to the guides corresponding with the needles which knit at the next feeder. Thus black stitches would appear on the plain wales of one web and red stitches would appear on the plain wales of the other web, i. e. black and red stitches alternately in the coursewise direction. By shogging the guides at appropriate times in relation to the needles, or vice versa, and operating the guides so that either black or red threads are lapped or wrapped on the plain needles knitting at both feeders, black or red stitches would be produced, in coursewise succession, on the plain wales or both webs thus forming solid black or solid red horizontal striping effects. Shogging and operating the guides so that black threads are served at both feeders for a course or courses alternately would produce solid black and red stripes alternately in the walewise direction of the fabric. Appropriate intermediate selection of the guides, or the needles, would produce a diversity of effects on the ground fabric between stripes. When a succession or all of the guides are supplied with threads all of the same character, e. g. red, the guides may serve all of the said threads to the bottom cylinder needles of one set at one feeder, and, thereafter, as the result of shogging at the appropriate time, may serve the bottom cylinder needles of the other set with the same threads at the next feeder, thus again producing solid horizontal stripes. Also by shogging at suitable intervals horizontal stripes may be produced in desired walewise sequence with or without other effects in the intervening courses of the ground fabric.

The shogging mechanism may also be adapted to produce shogged effects from the same threads in different wales of one or each of the webs so that inclined or diagonal, zig-zag, crossed and like lines of lap or wrap stitches are produced, or from different threads in the same wales so as further to diversify the pattern effect.

Means may also be provided for moving any desired bottom cylinder needle or/and a guide lengthwise relatively so that the embroidery thread is laid either below the hook suchwise as to be engaged by the needle hook to form a stitch,

or further from the hook, e. g. below the latch in the illustrated example (or well below the beard of a bearded needle) so as thus to be merely interconnected with the ground fabric to form loops, as distinct from stitches, as hereinbefore mentioned. For example, when needle selecting mechanism is provided the same mechanism, or an additional similar mechanism, may be adapted to move a desired needle or needles to one or the other of two alternative positions so that in one position lap or wrap stitches are formed, and in the other position merely loops are formed. Or a similar selecting mechanism, adapted to function in this way, may be provided in association with the guides for producing a like result.

What we claim then is:

1. A knitting machine which includes, in combination, two needle beds, two sets of needles, one half of each set being in alternating relationship in one bed and the remainder of each set in similar relationship in the other bed, feeders for introducing yarns to the said sets of needles, corresponding sets of cam systems for causing the respective sets of needles to knit independently, and mechanism for wrapping desired needles with embroidery thread.
2. A circular knitting machine which includes, in combination, superposed bottom and top needle cylinders, double-ended needles for operation in said cylinders, sliders in the cylinders for operating the needles, said needles and associated sliders being arranged in two independently operable sets wherein needles and sliders of one set alternate with the needles and sliders of the other set in each of the cylinders, feeders for supplying yarns independently to the respective sets of needles, different sets of cams for operating the said sets of needles, and embroidery mechanism comprising thread guiding means operable in conjunction with needles in the bottom cylinder and means for operating said guides so as to wrap desired bottom cylinder needles with embroidery thread.
3. A circular knitting machine which includes, in combination, a bottom needle cylinder, a cam box surrounding said cylinder, a superposed top cylinder, another cam box similarly surrounding said top cylinder, double-ended needles for operation in said cylinders, sliders in the cylinders for operating the needles, said needles and associated sliders being arranged in two independently operable sets wherein needles and sliders of one set alternate with the needles and sliders of the other set in each of the cylinders, and the sliders of the two sets being provided with knitting butts in respectively different planes, feeders for supplying yarns independently to the respective sets of needles, cam systems disposed at different levels in the bottom and top cam boxes for action on the butts in the different planes so that the two sets of needles knit respectively at spaced feeders, and embroidery mechanism comprising thread guiding means operable in conjunction with needles in the bottom cylinder and means for operating said guides so as to wrap desired bottom cylinder needles with embroidery thread.
4. A knitting machine which includes, in combination, two needle beds, two sets of needles, one half of each set being in alternating relationship in one bed and the remainder of each set in similar relationship in the other bed, feeders for introducing yarns to the said sets of needles, corresponding sets of cam systems for causing the respective sets of needles to knit independently, and embroidery mechanism comprising individ-

ually operable thread guides and means for so operating the said guides selectively that desired ones of corresponding needles in one of the needle beds are wrapped with embroidery thread.

5. A circular knitting machine which includes, in combination, superposed bottom and top needle cylinders, double-ended needles for operation in said cylinders, sliders in the cylinders for operating the needles, said needles and associated sliders being arranged in two independently operable sets wherein needles and sliders of one set alternate with the needles and sliders of the other set in each of the cylinders, feeders for supplying yarns independently to the respective sets of needles, different sets of cams for operating the said sets of needles, and embroidery mechanism comprising as many individually operable thread guides as there are needles of one set in the bottom cylinder and means for so operating the said guides selectively that desired ones of said bottom cylinder needles are wrapped with embroidery thread.

6. A circular knitting machine which includes, in combination, superposed bottom and top needle cylinders, double-ended needles for operation in said cylinders, sliders in the cylinders for operating the needles, said needles and associated sliders being arranged in two independently operable sets wherein needles and sliders of one set alternate with the needles and sliders of the other set in each of the cylinders, a plurality of feeders for supplying yarns independently to the respective sets of needles, different sets of cams for operating the said sets of needles and causing them to knit at the feeders alternately, cam means located between the knitting stations at the feeders for effecting transference of needles from one cylinder to the other, and embroidery mechanism comprising thread guiding means operable in conjunction with needles in the bottom cylinder and means for operating said guides so as to wrap desired bottom cylinder needles with embroidery thread.

7. A knitting machine which includes, in combination, two needle beds, two sets of needles, one half of each set being in alternating relationship in one bed and the remainder of each set in similar relationship in the other bed, feeders for introducing yarns to the said sets of needles, corresponding sets of cam systems for causing the respective sets of needles to knit independently, embroidery mechanism comprising individually operable thread guides and means for so operating the said guides selectively that desired ones of corresponding needles in one of the needle beds are wrapped with embroidery thread, and means for shogging the guides and needles relatively, for the purposes herein specified.

8. A circular knitting machine which includes, in combination, superposed bottom and top needle cylinders, double-ended needles for operation in said cylinders, sliders in the cylinders for operating the needles, said needles and associated sliders being arranged in two independently operable sets wherein needles and sliders of one set alternate with the needles and sliders of the other set in each of the cylinders, feeders for supplying yarns independently to the respective sets of needles, different sets of cams for operating the said sets of needles, movable thread guides for wrapping embroidery threads around desired needles in the bottom cylinder, a grooved carrier for said thread guides which carrier is arranged suchwise as to enable the guides to be moved in a plane at

right angles to the axis of the needle cylinders, and means for operating the guides.

9. A circular knitting machine which includes, in combination, superposed bottom and top needle cylinders, double-ended needles for operation in said cylinders, sliders in the cylinders for operating the needles, said needles and associated sliders being arranged in two independently operable sets wherein needles and sliders of one set alternate with the needles and sliders of the other set in each of the cylinders, feeders for supplying yarns independently to the respective sets of needles, different sets of cams for operating the said sets of needles, movable thread guides for wrapping embroidery threads around desired needles in the bottom cylinder, said guides being differentiated from each other by the provision thereon of patterning butts so disposed as to be located in different planes, a grooved carrier for the thread guides which carrier is arranged suchwise as to enable the guides to be moved in a plane at right angles to the axis of the needle cylinders, a selecting cam movable into any one of the aforementioned planes for action upon desired patterning butts for the purpose of advancing predetermined guides to wrap.

10. A circular knitting machine which includes, in combination, superposed bottom and top needle cylinders, double-ended needles for operation in said cylinders, sliders in the cylinders for operating the needles, said needles and associated sliders being arranged in two independently operable sets wherein needles and sliders of one set alternate with the needles and sliders of the other set in each of the cylinders, feeders for supplying yarns independently to the respective sets of needles, different sets of cams for operating the said sets of needles, movable thread guides for wrapping embroidery threads around desired needles in the bottom cylinder for the purpose of obtaining wrap striping effects, a grooved carrier for said thread guides which carrier is arranged suchwise as to enable the guides to be moved in a plane which is normal to the axis of the aforementioned cylinders, means for operating the guides, and means for shogging the thread guides over needles.

11. A circular knitting machine which includes, in combination, superposed bottom and top needle cylinders, double-ended needles for operation in said cylinders, sliders in the cylinders for operating the needles, said needles and associated sliders being arranged in two independently operable sets wherein needles and sliders of one set alternate with the needles and sliders of the other set in each of the cylinders, feeders for supplying yarns independently to the respective sets of needles, different sets of cams for operating the said sets of needles, movable thread guides for wrapping embroidery threads around desired needles in the bottom cylinder for the purpose of obtaining wrap striping effects, a grooved carrier for said thread guides which carrier is arranged suchwise as to enable the guides to be moved in a plane which is normal to the axis of the cylinders, means for operating the guides, and mechanism for effecting turning movements of the thread guide carrier independently of the needle cylinders for the purpose of shogging the thread guides, said mechanism comprising a stepped cam, a disc cam to which said stepped cam is connected, a support upon which said cams are mounted and which is fixed in relation to the needle cylinder, plungers arranged

for action upon the stepped cam to impart turning movement to the latter and hence also to the disc cam in one direction or the other, means for controlling said plungers in accordance with patterning requirements, and connections between said disc cam and the thread guide carrier whereby the latter can be shogged to a desired extent in one direction or the other.

12. A knitting machine which includes, in combination, two needle beds, two sets of needles, one half of each set being in alternating relationship in one bed and the remainder of each set in similar relationship in the other bed, a plurality of feeders for supplying yarns independently to the respective sets of needles, different sets of cams for operating the said sets of needles and causing them to knit at the feeders alternately, cam means located between the knitting stations at the feeders for effecting transference of needles from one needle bed to the other, and mechanism for wrapping desired needles with embroidery thread. 20

13. A knitting machine which includes, in combination, two needle beds, two sets of latch needles, one half of each set being in alternating relationship in one bed and the remainder of each set in similar relationship in the other bed, feeders for introducing yarns to the said sets of needles, corresponding sets of cam systems for causing the respective sets of needles to knit independently, embroidery mechanism comprising individually operable thread guides and means for operating said guides so that desired needles in one of the beds are wrapped with embroidery thread, and means for moving any desired needle and corresponding thread guide relatively so that an embroidery thread is laid below the latch of the needle, for the purpose herein described. 15

EDWIN WILDT.

HENRY HAROLD HOLMES.

JOHN CYRIL HERBERT HURD.
